Balmer & Son

United States Patent Office.

FREDERICK MERIWETHER, OF TAMOLA, MISSISSIPPI.

Letters Patent No. 71,895, dated December 10, 1867.

UTERINE SUPPORTER.

The Schedule referred to in these Letters Patent and making part of the same.

TO ALL WHOM IT MAY CONCERN:

Be it known that I, FREDERICK MERIWETHER, M. D., of Tamola, in the county of Kemper, and State of Mississippi, have invented a new and useful Improvement in Uterine Supporters, of which the following is a full, clear, and exact description, reference being had to the accompanying drawing, which makes part of this specification, and which represents a view in perspective of my improvement.

It is the object of my invention to produce a support for the uterus, which will act efficiently under all the necessities created by the movements of the patient, and the improvement herein claimed consists in combining the pessary-pillar with the truss by means of a copper bar, which will permit the pessary to be adjusted readily to the condition of the patient, as hereinafter described.

In the accompanying drawing, a pelvic spring, A, is shown, as provided with the ordinary leather cover and strap B. This spring serves as the base to support the other parts firmly, to prevent the pessary from moving about in consequence of the muscular movements of the body. A slot is cut vertically through the pelvic spring to receive a bar, C, which moves endwise in it, and can be held in any desired position by a set-screw, D. A spring, E, of copper, is secured at one end to this bar, and at the other to a pillar, F, which supports a pessary, G.

By this means the pessary can be adjusted higher or lower, as required, and fixed by the set-screw. The physician who applies it can also adjust the pessary so that it may incline backward or forward, or to the right or left, by bending or twisting the copper part E of the spring, to adapt it to the different positions of the womb. After it has once been adjusted properly, the wearer herself can remove and replace it at pleasure.

The stem F may be made of any suitable material, (gold, if preferred,) and is united with the spring E by a screw-connection, which admits of its removal for the purpose of being cleansed or repaired.

The pessary G is made small, not only for the sake of introducing it easily, but to prevent the expansion of the soft parts, and to allow the vagina an opportunity to contract to its normal size, and thus finally to support the womb without the aid of an instrument.

The spring is sufficiently elastic to permit the pessary to yield to obviate shocks, such as those caused by getting out of a carriage, or stepping off an elevation, and to bring the womb back gently into position again after its descent.

Having thus described my improved uterine supporter, what I claim therein as new, and desire to secure by Letters Patent, is—

The combination, as described, of the spring E, composed of copper or other soft metal, with the pessary, for the purposes set forth.

I also claim the combination, substantially as described, of the pelvic spring, the vertically adjustable bar and set-screw, the soft metal spring E, the pessary-pillar F, and the pessary, for the purposes specified.

In testimony whereof, I have hereunto subscribed my name.

FREDERICK MERIWETHER.
